FLECKED METALLIZED YARN
Walter G. Scharf, 243 Palmer Court,
Ridgewood, N.J. 07450
Filed Dec. 20, 1963, Ser. No. 332,019
2 Claims. (Cl. 161—175)

This invention relates generally to synthetic yarn for use in textile and in other applications, and more particularly to a method of producing a synthetic yarn having a flecked or dappled appearance resulting from the random distribution of metallic specks therein.

It has been known to produce metallized yarns by interlaminating two webs of transparent material with a layer of metal foil, the resultant sandwich then being slit to yarn size. By introducing pigment into the adhesive layers used to laminate the webs to the foil or by the use of various printing techniques, color effects may be imparted to the metallized yarn. However, it has not heretofore been possible to fabricate a yarn of synthetic material which is entirely transparent except for specks of metallized material embedded therein the length thereof.

Accordingly, it is the main object of this invention to provide a novel synthetic yarn of transparent material having metallic specks of different color randomly distributed therein. Because of the flecked effect provided by this yarn, there is created a new range of decorative possibilities in textile design, and it becomes feasible by the use of a yarn of the type disclosed herein, to produce fabrics of original and highly ornamental design, or to produce finishing effects heretofore obtainable at far greater expense only by the use of a multitude of differently colored yarns in combination with complex weaving procedures. Because of the non-continuous nature of the metallic coloration, a greater degree of design flexibility is available in the weaving and knitting process, and it becomes possible with the flecked yarn to produce shantung-like effects, among others.

Also an object of the invention is to provide a method and an apparatus for combining webs of transparent synthetic material with metallic threads of different color to produce a sandwich web which, when slit to yarn size, produces a flecked yarn of the type noted above.

Still another object of the invention is to provide a flecked yarn of high quality which may be manufactured and sold at relatively low cost.

Briefly stated, these objects are accomplished by a technique wherein two webs of transparent material and an array of metallized threads which lie at spaced parallel positions in a common plane, are simultaneously fed to laminating rolls, the array of threads feeding into said rolls being at the same time so manipulated as to cause the threads sandwiched between the webs to be sinuously arranged in meandering paths which repeatedly intersect the longitudinal axis of said webs, whereby when the resultant sandwich web is slit longitudinally to produce laminated yarns, each yarn incorporates those portions of said metallized threads which appear at the point of intersection.

For a better understanding of the invention, as well as other objects and further features thereof, reference is had to the following detailed description to be read in conjunction with the accompanying drawing, wherein:

FIG. 1 is a schematic drawing, in perspective, showing a technique for producing a laminated web which when slit forms a speckled yarn in accordance with the invention;

FIG. 2 illustrates, in perspective, the apparatus for slitting the laminated web;

FIG. 3 is a longitudinal section taken through one of the speckled yarns;

2

FIG. 4 is a plan view of the laminated web prior to slitting; and

FIG. 5 is a perspective view showing the speckled yarn in supported form.

5 Referring now to FIG. 1, in a system in accordance with the invention for producing a flecked yarn thread, two continuous webs of transparent thermoplastic material 10 and 11 are drawn from supply rolls 12 and 13 and are caused to travel into a laminating device constituted by pressure rolls 14 and 15. The webs may be constituted by cellophane, acetate, tri-acetate, acetate butyrate, polymerized ethylene glycol terephthalate (Mylar), or any other suitable transparent and flexible synthetic material. The thickness of the web for ordinary 15 yarn purposes should not exceed 2 mils, but of course other thicknesses may be used in other applications. The laminating rolls 14 and 15 and the wind-up reel 16 for the sandwich web are operated by a suitable drive system 17.

20 Fed between the webs 10 and 11 into laminating rolls 14 and 15, are a series of ribbon-like metallic threads 18A, 18B, 18C, etc., which are preferably less than one mil in thickness, disposed in spaced parallel relation and derived from a bank 19A, 19B, 19C, etc., of spools or 25 packages. The several threads from the spools pass through the respective openings of a reed 20 or similar device which serves to maintain the threads at their spaced positions. The reed 20 is caused, by a traversing mechanism 21 of any suitable design, to reciprocate relative to the bight of laminating rolls 14 and 15, whereby 30 the metallic threads enter between the webs at an angle relative to the direction of movement, this angle being continually shifted as the reed moves back and forth. The movement of the reed may be made irregular, rather than 35 periodic in order to obtain more random distribution of specks.

The undersurface of top web 10 is coated with a clear transparent adhesive in liquid form applied thereto by means of a roll 22 operating in conjunction with an 40 adhesive well 23. Simultaneously a layer of adhesive is applied to the top surface of the bottom web 11 by means of a roll 24 operating in conjunction with an adhesive well 25. Suitable transparent adhesive for this purpose may be formed of polyvinyl resin, and in other formulations, such as those disclosed in the patent to Lacy, 45 2,772,994.

Thus as the series of threads feeds between the adhesive-coated webs, a sandwich web 26 is formed in which the webs and the metallic threads are interfacially bonded. 50 Since the threads are introduced at a constantly shifting angle to the direction of web movement, the threads in the sandwich assume sinuous configurations in which each thread runs in a meandering path with respect to the longitudinal axis of the sandwich web.

55 After the sandwich web 26 is rolled up on roll 16 and the adhesive layers fully dried or cured, the sandwich web 26 is unwound and conveyed through a conventional slitter, such as the bank 27 of equi-spaced knives shown in FIG. 2, which serves to cut the web into a series of 60 separate flat, flecked yarns 26A, 26B, 26C, etc. In practice, the web may first be cut into broad bands which are thereafter slit to the ultimate yarn size.

The nature of the individual yarns is best appreciated by referring again to FIG. 4, wherein the longitudinal section of the web, which when slit, forms an individual 65 yarn 26X, is delineated by dashed lines running parallel to the longitudinal axis X of the sandwich web. It will be evident that intersecting the longitudinal path of the individual yarn sections of the web are portions of metallic threads 18E, 18F, 18G, 18H, 18G, 18E, 18F, 18G, 18H, in succession. Since the paths of the threads weave back and forth with respect to the straight path of the in-

dividual yarn, only that portion of the thread which appears at the intersection is trapped within the yarn. It will also be seen that the spacings between the points of intersection are not uniform and appear random. Hence, as shown in FIG. 3, in section, each yarn ribbon is composed of a transparent bottom ply P_1 , a transparent top ply P_2 , and randomly distributed metallic specks S_1, S_2, S_3 , etc., the specks and plies being adhesively interconnected. The metallic specks are visible on either side of the yarn. It is to be understood that when the metallic specks themselves are formed with thermoplastic coatings, these may be combined with the transparent plies by heat-sealing techniques and without adhesive. However to bond together the transparent plies in the areas thereof not including metallic specks, an adhesive should be applied to one surface thereof.

The metallic threads of different color fed into the combiner rolls may be in any known form, including narrow ribbons of pure metal foil, or metal foil sandwiched between plies of transparent synthetic plastic material, as disclosed in Prindle et al. Patent 2,714,569. Preferably, the metallic threads are of the non-laminated type made in accordance with Scharf Patent 2,974,055, wherein a base layer of thermoplastic material is vacuum coated with a metallic deposit, such as aluminum, in a thickness not exceeding one fifty-thousandths of an inch, the metallic deposit then being coated with a transparent plastic in liquid form which, when dried and cured, forms a thin film related structurally to the base material and adhering directly to the metallic deposit. Since the thickness of this non-laminated thread is mainly determined by that of the base web, it is possible with a Mylar base to produce metallized threads of less than one mil in thickness and of relatively high tensile strength.

It is important that the metallic thread be exceptionally thin, for being sandwiched between two plies, it contributes to the ultimate thickness of the flecked yarn. In order, therefore, to produce a thin, flecked yarn, it is essential that the metallic threads incorporated therein be extremely thin. Moreover, such thinness on the part of the metallic threads is necessary in order to permit effective lamination of the top and bottom webs in the clear areas therebetween in which the threads are absent.

When the flecked yarn is knit or woven into a fabric, the random distribution of the metallic specks therein produces a fabric having an unusual and highly decorative appearance. If, for example, the flecked yarn appears

only in the warp, and a clear weft yarn is interwoven therewith, then the streaks of differently colored metallic flecks all run in the same direction to produce a shantung-like effect. But altogether different effects are obtainable when using flecked yarns in both the warp and woof directions, since then the metallic specks which run linearly with the yarns across each other in the warp and woof directions.

If, as shown in FIG. 5, the flecked yarn FY is supported on a core SY, such as a solid-color cotton or synthetic filament, say in matt black, this solid color affords a ground which sets off the flecked metallic colors in the flecked yarn, thereby opening up another range of decorative effects.

What is claimed is:

1. A flecked yarn comprising:

(a) top and bottom ribbon-like outer plies of clear transparent flexible material formed of polymerized ethylene glycol terephthalate, and
 (b) specks of metallic threads sandwiched between said outer plies and laminated thereto, said specks being formed by a metal coating formed on a clear thermoplastic base, which coating is covered by a clear thermoplastic film directly adherent thereto, which specks are heat-sealed to said outer plies.

2. A yarn as set forth in claim 1, wherein said specks are randomly distributed.
